SHOE STIFFENER AND METHOD OF MAKING THE SAME

Filed Jan. 29, 1924

UNITED STATES PATENT OFFICE.

HARRY H. BECKWITH, OF BROOKLINE, MASSACHUSETTS.

SHOE STIFFENER AND METHOD OF MAKING THE SAME.

Application filed January 29, 1924. Serial No. 689,269.

In the manufacture of box toe blanks of a felt or felt-like fabric saturated with a thermo-plastic material such as asphalt, resin, Montan wax, and the like, the fabric 5 is first saturated with melted thermo-plastic material. After cooling, the blanks are cut in approximately semi-circular form and are then skived at their edges to secure a taper from the center to the edges. It has been 10 found that no matter how well the skiving has been done the extreme edges are sometimes too thick when employing very thin leather in shoe fabrication, the result being that a slight ridge may show at the edge of 15 the toe toward the vamp. Likewise it is often desirable to eliminate any hard and fast line between the relatively stiff toe portion and the relatively limp vamp portion.

It is the object of this invention to reduce 20 the edge of the stiffener blank to a point of thinness and character of stiffness so that no hard and fast line will appear in the shoe. This may be done by subjecting the tapered edge to heat and pressure so as to cause the 25 thermo-plastic material to more or less exude therefrom, it being preferable to support the blank on some sort of a bibulous support which will absorb the exuded material and prevent it from remaining on the surface of 30 the blank. By causing this treatment to be effected to a gradually decreasing extent back from the edge of the blank the relative proportion of thermo-plastic to fibrous material may be gradually increased inwardly from 35 this edge so that the transition from substantially no stiffness at the extreme edge where the thermo-plastic is mostly removed to the stiffness of the main portion of the blank may be gradual and imperceptible. 40 Preferably the bibulous support on which the blanks are carried during this treatment is formed of fibrous material of the same character as that from which the shoe stiffeners are made. In this event the thermo-plastic absorbed thereby is not lost since the 45 support itself may, after having functioned in this manner, be more completely saturated with thermo-plastic material and then itself be cut into stiffener blanks which in 50 turn may be treated in the manner hereinbefore set forth.

For a more complete understanding of this invention reference may be had to the accompanying drawings in which 55 Figure 1 represents a box toe blank to be treated in accordance with this invention.

Figure 2 is a section on line 2—2 of Figure 1.

Figure 3 is a top plan of a mechanism designed to effect the further treatment of the 60 blank.

Figure 4 is a side elevation of the same.

Figure 5 is a detail section on an enlarged scale on line 5—5 of Figure 4.

Figure 6 is a detail section illustrating a 65 modification.

Referring to these drawings, 1 indicates a blank cut from fibrous sheet material saturated with thermo-plastic and skived to form thin marginal portions. The flatter 70 margin 2 of this blank in the finished shoe underlies the rear portion of the toe at the junction between the toe and the vamp. Blanks cut in this manner may then be laid on a belt 3 (as shown in Figure 3) which 75 belt may be suitably supported over feed rollers 4 and 5 as to permit the blanks to be fed in succession beneath a heated ironing pressure roller 6. The periphery of this pressure roller is formed tapered as at 7, the taper 80 preferably being more obtuse than that of the skived margin 2 with which it is intended to contact. This roller may be heated as by any suitable means, as herein shown an electric heating unit 8 being carried therein and supplied by an electric current through a pair 85 of slip rings 9 on the roller driving shaft 10 which may be driven by a pulley 12. The portions 2 of the stiffener blanks are caused to pass in succession beneath the edge 7 of 90 the roller which bears hard against the extreme edge portion of the blank and with a gradually lighter pressure inwardly from this edge. This roller should be heated sufficiently to cause the thermo-plastic material 95 to be melted and exude from the fibrous foundation, the belt support 3 beneath it being of such a character as to absorb the melted material as fast as it exudes so that no deposit of this material remains on the face 100 of the blank. The heat and pressure being applied most forcibly to the extreme edge causes the extreme edge to lose a greater proportion of its thermo-plastic than portions inwardly therefrom and the roller face gradually leaves contact with the stiffener inwardly from this edge so that no hard and fast line is left between the portions from which the thermo-plastic is removed and those portions substantially unaffected by the 110 treatment. If it were attempted to exert heat and pressure over a very definite area, a

ridge of thermo-plastic material about the outline of this area would be produced which would be liable to show in the finished shoe. By causing the face of the treating roller to 5 gradually recede from the blank, no such effect is produced. The lower feed roller 5 is employed to receive the thrust from the heated roller 6 and after passing this roller a stripper member 16 is positioned to remove 10 the blanks from the supporting belt 3 before they have become sufficiently cool to strongly adhere thereto.

In place of using a heated roller a non-rotatable iron such as shown in Figure 6 at 15 20 may be employed. This iron may be heated as by means of the electric resistance element 21 carried thereby and may have an inclined face 22 preferably of more obtuse inclination than the marginal portion of the 20 stiffener blank to impart a decreasing treating action thereon back from the edge in the same manner as described in connection with the heated roller. A support 23 of any suitable description may be utilized in connection with this iron to take the thrust therefrom. Of course in place of forming the treating face 22 of the iron with a more obtuse inclination than that of the skived face of the blank, the iron having a flat face may 30 be applied to the shank in such a manner with the face at one angle to the work surface that the desired gradual decrease in pressure may be effected back from the edge of the blank. This pressure acts not only to 35 remove the thermo-plastic from the edge of the blanks, but also causes them to be condensed and thinned to such a degree that no line is apparent at the rear edge of the stiffener in the finished shoe even though 40 very light stock may be used in the shoe upper.

Having thus described this invention it should be evident to those skilled in the art that various changes and modifications might 45 be made therein without departing from its spirit or scope as defined by the appended claims.

I claim:

1. That step in the process of preparing 50 shoe stiffeners from fibrous sheet material saturated with thermo-plastic material, which comprises removing a portion of the thermo-plastic only, from a margin of a blank cut from the saturated material.

55 2. That step in the process of preparing shoe stiffeners from fibrous sheet material saturated with thermo-plastic material, which comprises removing at the margin of a stiffener blank cut from the saturated sheet 60 a gradually decreasing proportion of the thermo-plastic to the fibrous material back from the edge thereof.

65 3. The steps in the process of preparing shoe stiffeners from fibrous sheet material saturated with thermo-plastic material which

comprises subjecting the margin of a stiffener blank cut therefrom to heat and pressure sufficient to cause exudation of the thermoplastic material, and removing such exuded material.

70 4. The steps in the process of preparing shoe stiffeners from fibrous sheet material saturated with thermo-plastic material which comprises subjecting the margin of a stiffener blank cut therefrom to heat and pressure of 75 progressively increasing amount toward the edge thereof, the heat being sufficient to cause exudation of the thermoplastic material under such pressure, and removing the exuded material.

75 5. The method which comprises superposing a stiffener blank comprising fibrous sheet material saturated with thermo-plastic material on unsaturated fibrous material previous to the incorporation of such blank in a 80 shoe, and subjecting a marginal portion of said blank to heat to cause the thermo-plastic material in that portion to partly exude therefrom and to be absorbed by the underlying 85 unsaturated material.

90 6. The method which comprises superposing a stiffener blank comprising fibrous sheet material saturated with thermo-plastic material on similar unsaturated fibrous material previous to the incorporation of said blank in a 95 shoe, subjecting a marginal portion of said blank to heat to cause the thermo-plastic material in that portion to partly exude therefrom and be absorbed by the underlying unsaturated material, completing the saturation 100 of said underlying material, and making stiffeners therefrom.

105 7. The method which comprises superposing a stiffener blank comprising fibrous sheet material saturated with thermo-plastic material on similar unsaturated fibrous material previous to the incorporation of said blank in a shoe, subjecting a marginal portion of said blank to heat to cause the thermo-plastic material in that portion to partly exude 110 therefrom and be absorbed by the underlying unsaturated material, completing the saturation 110 of said underlying material, cutting it into stiffener blanks, and treating these 115 blanks in the same manner to make stiffeners therefrom.

120 8. The method which comprises superposing a stiffener blank comprising fibrous sheet material saturated with thermo-plastic material on a bibulous support previous to the incorporation of said blank in a shoe, and subjecting a portion of said blank to heat and pressure to cause the thermo-plastic material in that portion to partly exude therefrom and be absorbed by the underlying bibulous 125 material.

130 9. That step in the manufacture of shoe stiffeners formed of fibrous sheet material saturated with a thermo-plastic which comprises applying to a marginal tapered por-

- tion of a blank cut from said sheet a heated iron having its sheet treating face presented at a more obtuse angle than the taper of said margin to have a gradually decreasing effect back from the edge thereof.
10. That step in the manufacture of shoe stiffeners formed of fibrous sheet material saturated with a thermoplastic which comprises applying to a marginal tapered portion of a blank cut from said sheet while said blank is carried on a bulbous support a heated iron having its sheet treating face presented at a more obtuse angle than the taper of said margin to have a gradually decreasing effect back from the edge thereof.
11. A shoe stiffener blank comprising fibrous sheet material saturated with thermo-plastic material and cut to shape, a marginal portion of the blank containing a progressively smaller proportion of thermo-plastic to fibrous material toward its edge.
12. A shoe stiffener blank comprising fibrous sheet material saturated with thermo-plastic material and cut to shape, a marginal portion of the blank being shaped to a thin edge and containing a progressively smaller proportion of thermo-plastic to fibrous material toward said edge.
13. A shoe stiffener suitable for assembly in a shoe upper and having a marginal portion of progressively decreasing stiffness relative to its thickness toward its edge.
14. A shoe stiffener suitable for assembly in a shoe upper and having a marginal portion of progressively decreasing thickness and degree of stiffness relative to thickness toward its edge.
15. A shoe stiffener suitable for assembly in a shoe upper and comprising fibrous sheet material saturated to different extents in different portions with a thermo-plastic.
16. A toe stiffener suitable for assembly in a shoe upper and comprising fibrous sheet material saturated with a stiffening agent, there being a smaller proportion of stiffening agent to fibrous material along that margin of the blank positioned rearwardly when the stiffener is incorporated in the shoe than in other portions thereof.
- In testimony whereof I have affixed my signature.

HARRY H. BECKWITH.
